UNITED STATES PATENT OFFICE

2,553,921

CONTINUOUS CASTING APPARATUS

James Fernando Jordan, Huntington Park, Calif.

Application April 12, 1949, Serial No. 87,048

1 Claim. (Cl. 22—57.2)

1

My invention relates to the art of continuously-casting molten metal to form semi-finished shapes.

This application is a continuation-in-part of my application, Serial No. 54,324, filed on October 13, 1948, now abandoned.

Present and past methods of continuously-casting semi-finished steel shapes employ water-cooled molds into the top of which the molten steel is poured and out thru the bottom of which the solidified steel shape is drawn. These methods suffer from the disadvantage that it is extremely difficult to keep the surface of a bath of molten steel free from slag and/or surface-oxide films; and these methods also suffer from difficulties arising from the fact that it is necessary to feed the molten steel into the water-cooled mold at a substantially-constant rate, else the rate of solid shape withdrawal may get out of balance with the rate at which the molten steel is being introduced into the mold.

My invention is an apparatus for continuously-casting semi-finished steel, or other metal, shapes that eliminates the mentioned objectionable features of past and present casting methods.

My apparatus consists of a water-cooled mold that is inserted into the bath of molten metal from a position that lies above the upper surface of said bath, said water-cooled mold being positioned so that it extends below said surface of said bath of metal and extends partly above said surface of said bath. The casting operation proceeds as the molten metal flows into the mold opening that is submerged; solidifies into the desired shape within said mold; and is continuously withdrawn, as the final solidified shape, from the mold opening that is positioned above said surface of said bath. My casting apparatus thus permits the continuous withdrawal of the desired metal shape up from, and out of, the bath of molten metal. Furthermore, my apparatus may be operated so that it will continuously cast either solid shapes—such as rounds, squares, sheet, plate, etc., or said apparatus may be employed to cast hollow shapes—such as pipe.

Figure 1 shows a form of my casting apparatus in position in a bath of molten metal.

Figure 2 shows section 2—2, indicated in Figure 1.

Figure 3 shows my casting apparatus arranged to cast pipe.

Figure 4 shows section 4—4, indicated in Figure 3.

2

Figure 5 shows a modification of my apparatus of Figure 1.

Figure 6 shows another modification of my apparatus of Figure 1.

Figure 7 shows still another modification of my apparatus of Figure 1.

Figure 8 shows my apparatus of Figure 1, modified to cast sheet or plate.

Figure 9 shows another modification of my apparatus.

In Figures 1 and 2, the mold is formed of a metal pipe 15 that is open at the top and bottom. Mold pipe 15 is cooled by means of a concentric arrangement of pipes 17 and 16, which pipes 17 and 16 are spaced around mold-forming pipe 15, so as to form water-circulating spaces 15A and 15B. Spaces 15A and 15B are separately closed at their tops by means of water-jacket top end 16A, and said spaces 15A and 15B are confined to join each other by water-jacket bottom end 18A that connects pipe 16 with mold pipe 15, and said spaces are permitted to join each other by connecting space 18 that is formed as pipe 17 reaches not quite down to water-jacket bottom end 18A. At, or near, the top of the water-jacketed mold, pipe connection 13A penetrates the arrangement to connect space 15A with a source of cooling-water 13; and at, or near, said top of the water-jacketed mold, pipe connection 12A penetrates the arrangement to connect with space 15B, so as to permit the heated water 12 to leave said space 15B. That portion of pipe 16 which is to be exposed to direct contact with liquids 20 and 22, and that portion 30 of pipe 16 which is to lie immediately above slag layer 20, is shown covered with refractory covering 14, said covering 14 being caused to entirely cover the submerged portion of pipe 16, except for opening 19 that connects the casting zone 35 within pipe 15 with molten metal bath 22.

The cooling water 13 enters space 15A thru connection 13A; flows down thru said space 15A; cooling mold pipe 15 as it so flows; and then carries the absorbed heat away from space 15A 45 by entering space 15B via space 18, said space 15B conducting the heated water out of the process via connection 12A—cooling pipe 16 and covering 14 as the water flows up thru space 15B.

The casting apparatus of Figures 1 and 2 may be placed in operation by first inserting a length of the metal that is to be cast 11 in the mold cavity within mold pipe 15, said insert metal 11 being large enough in diameter to substantially fill said cavity, yet not so large that said inserted metal 11 cannot be readily moved up and down within said cavity. Inserted metal 11 should ex-

tend almost to the bottom of mold pipe 15, and should rise above said mold pipe 15 far enough to connect with lifting means 10 (not shown).

With inserted metal 11 in place, and with cooling water 13 circulating thru spaces 15A and 15B, the casting apparatus may be prepared for immersion by strongly preheating refractory covering 14 that forms the bottom of the mold, particularly should opening 19 be strongly preheated. One of the simplest methods of preheating opening 19 is to lower the casting apparatus until the bottom of said opening 19 is an inch, or so, above the molten slag layer 20, so as to permit said layer 20 to preheat opening 19 by radiation. Covering 14 and opening 19 may be preheated also by simply playing flame thereupon.

With refractory covering 14 and opening 19 preheated to a temperature that lies above the melting point of the metal that is being cast, the casting apparatus may be lowered into casting position by slowly lowering opening 19 into metal bath 22 far enough to prevent slag layer 20 from entering opening 19 during the casting operation that is to follow. This lowering operation should be performed so that slag 20 does not enter opening 19 as the apparatus is immersed in metal bath 22. One way to avoid trapping slag 20 in opening 19 is to thicken up slag layer 20 in the vicinity of the proposed point of immersion, and, then, by pushing back the thickened slag, expose an area of bare molten metal into which the casting device may be introduced.

At the moment when preheated opening 19 is immersed far enough below the surface of metal bath 22 to cause said metal to flow into contact with the bottom end of inserted shape 11 to form zone of metal solidification 9, means 10 should be caused to slowly start to lift metal shape 11 up from, away from, and out of, the mold formed by pipe mold 15, and, as said shape 11 is slowly lifted out of the mold, the molten metal that forms bath 22 will enter pipe 15 via opening 19, and will thereupon flow towards, and will contact, said zone of solidification 9. Thus, metal shape 11 that is being continuously withdrawn out of the top of pipe mold 15 is being formed, and built up, at the zone of contact between said shape 11 and the molten metal that flows into said mold via opening 19. This zone of contact 9, being at the same time the zone of solidification 9, is definable as that point where the cooling metal has cooled enough to possess sufficient strength to support its own weight, in view of the lift exerted within said mold by atmospheric pressure acting downward upon surface 20A.

The general shape and location of zone of metal solidification 9 will depend upon the rate at which shape 11 is being lifted out of pipe mold 15. Thus, at a comparatively slow rate of shape 11 withdrawal, the general contour of zone 9 may be similar to zone 9 in Figure 1. As the rate of shape 11 withdrawal is increased, however, zone 9 will elongate out as the last point of metal solidification—the peak at the center of zone 9—moves up away from the bottom of the mold. The rate of withdrawal of shape 11 may be increased until the peak that represents the last point of solidification has risen to a point that lies so far above bath surface 20A that atmospheric pressure on said surface 20A can no longer support the molten and/or pasty metal that lies at the center of shape 11. When this happens, a hole will begin to appear in shape 11.

When the rate of withdrawal has been in-

creased until a hole begins to appear at the center of cast shape 11, my casting apparatus is producing cast pipe.

Figures 3 and 4 show my apparatus producing cast pipe. Here, the concentrically-arranged mold is formed as pipes 31 and 30 are spaced around mold pipe 37. Cooling-water 29 is shown flowing down thru space 37A, into space 37B via passage 39, up thru space 37B, and out of the mold via stream 28. The outside of the casting device is shown protected against heat by refractory covering 32, said covering 32 being penetrated at the bottom by opening 36, up thru which the molten metal in metal bath 35 flows to form a pool of molten metal within mold pipe 37. Surface 38 is the surface of said metal pool within mold pipe 37.

When the rate of withdrawal of shape 11 in Figure 1 is increased until a hole is being formed at the center of said shape 11, said hole will contain a partial vacuum if metal bath 22 consists of metal that does not evolve gas during the casting operation, and said vacuum will tend to lift, or suck, the molten metal up into mold pipe 15. When this partial vacuum is destroyed, either as the result of the evolution of gas during the solidification of the metal or as the result of the cutting off of shape 11 after said shape 11 has passed by lifting means 10—thus permitting atmospheric pressure to gain entry into said evacuated hole within shape 11, then the level of the molten metal within mold pipe 15 will fall below that level maintained with the help of said vacuum.

Once atmospheric pressure has gained entry into the evacuated hole within said shape 11, my apparatus will continuously cast metal pipe in the manner shown in Figures 3 and 4. Here, pipe 27 is being withdrawn from mold pipe 37 so fast that the chilling effect of cold mold pipe 37 is not sufficient to cause the zone of solidification 40 to bridge entirely across the mold cavity formed within mold pipe 37, with the result that when pipe 27 has been lifted above molten metal surface 38, the casting operation ceases, and the resulting pipe 27 will possess an inside diameter that is substantially equal to the diameter of said surface 38.

The inside diameter of pipe 27 may be increased by increasing the rate of withdrawal of said pipe 27, and, conversely, the inside diameter may be decreased by decreasing the rate of withdrawal. In fact, said inside diameter may be decreased to that point where zone of solidification 40 will bridge entirely across the mold cavity, resulting in the conversion of the operation into the production of a solid shape, as in Figure 1. And so, my apparatus may be shifted from solid shapes to pipe, and from pipe to solid shapes, with only a slight change in the method of operating said apparatus.

Surface 38 may be expected to be slightly below surface 41A, due to the viscosity of the metal that lies adjacent to zones 40; however, the pressure of gas 26 upon said surface 38 will effect the relative levels of said surfaces.

Gas 26 may be the atmosphere, or said gas 26 may be a gas selected to protect surface 38 from oxidation. Thus, when casting steel, copper, aluminum, magnesium, brass, bronze, etc., gas 26 may be nitrogen or carbon monoxide.

The pipe casting operation of Figure 3 may be started in the described manner, or said operation may be started by first inserting in mold pipe 37 a pipe whose outside diameter is only

slightly less than the inside diameter of pipe 37, and then preheating opening 36 in the described manner prior to inserting the casting device into bath 35.

The solid shape shown in Figures 1 and 2 need not necessarily be round, but may be any other desired shape—for example, shape 11 may be an oval, square, rectangle, a hexagon with flat faces, a hexagon with concave faces; etc.

Means 10 and/or 25 may be any convenient means for lifting the cast shape out of the continuous mold. Means 10 and/or 25 may be the human hand, rolls, a crane, a hoist, a magnet, a hydraulic jack, etc. The main requisite is that said means 10 and/or 25 be capable of lifting said cast shape in a uniform and controllable manner.

Mold pipe 15 and/or mold pipe 37 may be constructed of any metal whose thermal conductivity is high. Thus, for example, the mold pipe may be made of copper, brass, bronze, steel, etc. The inside diameter of the mold pipe may ordinarily be uniform from top to bottom, for the normal shrinkage of most metals will provide the clearance required between the cast shape and the mold pipe in order to prevent binding therebetween. If the device is being employed to cast a metal that tends to bind, then the inside diameter of the mold pipe may be tapered slightly, big end up.

The function of the refractory coverings 14 and/or 32 on the sides and bottoms of pipes 16 and/or 30 is to prevent the cooling action of said pipes from cooling the contacting metal bath to the point of solidification; for, if the metal starts to solidify on the outside of the casting device, it may not be long before the cast shape will be welded to metal that has solidified on said outside of the device. This would quickly bring the casting operation to a halt. The constriction of the bottom openings of said molds by means of refractory coverings is in keeping with this effort to deliver the molten metal to the zones of solidification. It is my intention that the refractory openings 19 and 36 be heated so high that no metal will solidify in the immediate vicinity of said openings.

This function of the bottom opening of my mold is the more important, the closer the temperature of the metal bath is to the melting point of the metal. If a metal is being cast out of a bath whose temperature lies so far above the melting point of said metal that said bath shows little tendency to solidify in the immediate vicinity of, or within, said opening, even though said opening is not constricted in the manner shown in Figures 1, 3, 6 and 9, then a mold bottom similar to Figures 5 and 7 may be employed. Figure 5 serves to emphasize the fact that the function of a refractory covering, such as 51, is to prevent the molten metal from solidifying in the vicinity of the outside of the bottom opening of the mold, such as 52; that is, the extension of said covering 51 up along the sides of mold 46 is not necessarily required for the successful operation of my mold, such extension—as shown in Figures 1 and 3—merely aids in preventing the metal from solidifying against the side of the mold. Such solidification of metal on the side of the mold will not interfere with the operation of said mold unless the solidification process extends to the bottom of said mold. In Figure 5, shape 45 is shown being drawn out of mold 46, said shape 45 being formed at zone of solidification 50 as molten metal 49 flows into said mold 76

via opening 52. Opening 52 in bottom covering 51 conforms in size and shape to the bottom opening of mold pipe 46A. Slag layer 47 contacts metal bath 49 at slag-metal interface 48.

- 5 In Figure 7, shape 61 is shown being drawn out of mold 62, said shape 61 being built up at zone of solidification 66 as molten metal 65 flows into the mold via opening 67. In Figure 7, the solidification of molten metal 65 on the bottom of mold 62 is prevented by forming said mold bottom of a metal whose thermal conductivity is low—heat resisting steel containing 25% chromium and 12% nickel, for example—in comparison with the thermal conductivity of the mold pipe that forms 10 the casting cavity—a mold pipe of copper, for example. With both said 25—12 bottom and said copper mold pipe being cooled by the same stream of water, said copper mold pipe will chill the molten metal much faster than said 25—12 bottom, with the result that said 25—12 bottom will offer a hotter surface to bath 65; the thicker said 25—12 bottom, the hotter will be the surface exposed to bath 65. The arrangement of Figure 7 will be effective only if the temperature gradient 25 thru said bottom is so steep that the outside surface—the surface in contact with bath 65—of said bottom is above the melting point of the metal that is being cast—a situation that may only be achieved when the melting point of the 30 metal that is being cast is well below the melting point of said 25—12 bottom.

The arrangements of Figures 5 and 7 may be made more effective by extending the mold bottom or the mold bottom covering so that they 35 constrict the opening thru which the molten metal must flow in order to reach the zone of solidification, as is shown in Figures 1, 3 and 6. In Figures 1 and 3, this constriction of the size of openings 19 and 36 by coverings over the mold 40 bottoms will improve the operation of the molds by decreasing the likelihood of the solidification of metal within, or immediately outside of, said openings; for, not only does such constriction remove said openings to a position more remote 45 from the effect of the cooling water, but the resulting smaller openings offer less exposed refractory surface to the molten metal passing thereby, resulting in the more easy maintenance of said openings in the hot condition required if 50 said metal is to be prevented from solidifying therein.

Figure 6 shows how a casting device of the type shown in Figure 7 may be improved in a manner that is analogous to the improvement shown in 55 Figures 1, 3 and 9. In Figure 6, shape 53 is being drawn out of mold 54, said shape 53 being built up at zone of solidification 58 as metal 57 enters the mold via opening 59. Opening 59 is 60 being extended to constrict said opening 59 in the manner indicated. Said extension removes opening 59 to a position more remote from the cooling water within the mold, resulting in the more easy maintenance of said opening in the highly-heated condition that is required if metal is to 65 be prevented from solidifying in, or immediately outside of, said opening 59.

The improved design of Figures 1 and 3 may be 70 still further improved by a design similar to the one shown in Figure 9. Here, shape 70 is being drawn out of mold 72, said shape 70 being built up at the zone of solidification shown within said mold 72. Water 73 is the cooling-water that is being circulated within mold 72. Metal bath 75 is shown flowing into said mold 72 thru an open-

ing 11 formed by refractory covering 14, said covering 14 being caused to extend into the bottom opening of said mold 12, so as to assure the delivery of metal 15 to within mold 12 before the solidification process begins.

While Figure 2 is section 2-2 in Figure 1, and shows the cast shape to be round in cross section, Figure 1 may be employed also to portray a section thru my apparatus when said apparatus is being employed to cast sheet or plate, in which case section 2-2 must be portrayed substantially as shown in Figure 8.

In addition to steel, my casting apparatus may be employed to cast copper, brass, bronze, aluminum, cast iron, magnesium, etc.

Having now described several forms of my invention, I wish it to be understood that my invention is not to be limited to the specific form or arrangement of parts herein described and shown, except insofar as such limitations are specified in the appended claim.

I claim as my invention:

In a continuous casting apparatus having a container for holding a bath of molten metal, an open-ended, water-cooled mold suspended in the container with its upper end above the molten metal level in the container and its lower end below said molten metal level, and means for with-

10 drawing solidified metal from the top of the mold, the combination therewith of a covering of a non-metallic refractory material surrounding the outer surface of the mold, said covering having 15 at the lower opening in the mold an opening smaller than that of the mold, said covering preventing molten metal from solidifying on any part of the mold except the mold cavity, which is filled through the opening in said covering.
